Doris Reinfeld,
INVENTOR

BY *Victor J. Evans*

ATTORNEY

P. Hickey

WITNESS:

UNITED STATES PATENT OFFICE

DORIS REINFELD, OF AKRON, OHIO

BABY BAND

Application filed April 16, 1928. Serial No. 270,566.

This invention relates to infants' abdominal bands and its general object is to provide such a band that is shaped so as to conform to the shape and size of the body of an infant when applied, with the result a perfect fit is assured as well as complete support, without binding or discomfort.

A further object of the invention is to provide an abdominal band for infants, that can be applied in an easy and expeditious manner and requires only a single fastening means therefor, such as a safety pin.

Another object of the invention is to provide an abdominal band of the character set forth, that is simple in construction, inexpensive to manufacture and efficient in operation and service.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a front elevation of the band forming the subject matter of the present invention and showing the same in applied position.

Figure 2 is a transverse sectional view taken through the band when in applied position.

Figure 3 is a view of the band in elevation.

Referring to the drawings in detail, it will be noted that the band is provided with a relatively wide intermediate portion 1 having an outwardly curved upper edge 2 and an inwardly curved lower edge 3.

From the intermediate portion 1, the band gradually tapers toward its respective ends, and the upper edges of the end portions, which for distinction are indicated by the reference numeral 4 are inclined to a greater degree than the lower edges thereof as will be noted upon inspection of Figure 3. The upper edges of the inner portions are likewise slightly curved inwardly upon themselves as at 5.

Formed approximately at the juncture of

one of the end portions with the intermediate portion is a slit 6 which may have its edges reinforced in any well known manner.

The band of course may be made from a single strip of material, but is preferably formed from two strips secured together at their edges. If a single strip is employed, the edges may be reinforced as will be readily apparent.

The intermediate portion of the band forms the front supporting means and the band is wrapped about the body with one of the end portions inserted through the slit, and the ends are then disposed in overlapping engagement and secured together through the instrumentality of a safety pin or like fastening means 7.

From the above description and disclosure of the drawings, it will be obvious that I have provided an infant's abdominal band that is so shaped that it will conform to the size and shape of the body of the infant, and can be applied in an easy and expeditious manner with very little effort.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

An abdominal band for infants comprising a relatively wide intermediate portion having an outwardly curved upper edge and an inwardly curved lower edge, tapered end portions formed with said intermediate portion and having their upper edges inclined to a greater degree than the lower edges thereof, said band being provided with a slit for the passage of one of said end portions, and means for securing said end portions together in overlapped relation.

In testimony whereof I affix my signature.

DORIS REINFELD.
